The ornamental design of a compound miter saw slide bar mechanism, as shown and described.

DESCRIPTION

FIG. 1 is a perspective view of the compound miter saw slide bar mechanism;

FIG. 2 is a side view of the compound miter saw slide bar mechanism;

FIG. 3 is an opposite side view of the compound miter saw slide bar mechanism of FIG. 2

FIG. 4 is a top view of the compound miter saw slide bar mechanism;

FIG. 5 is a bottom view of the compound miter saw slide bar mechanism;

FIG. 6 is an end view of the compound miter saw slide bar mechanism; and,

FIG. 7 is an opposite end view of the compound miter saw slide bar mechanism of FIG. 6.

The broken line showing of portions of a miter saw is for illustrative purposes only and forms no part of the claimed design.
